TERRY SELVAGE FILLING HOLDER
AND METHOD

Ivar O. Meberg, Spry, N.C., assignor to Fieldcrest Mills, Inc., Spry, N.C., a corporation of Delaware
Filed Nov. 10, 1960, Ser. No. 68,382
7 Claims. (Cl. 139—195)

This invention relates to looms for weaving terry fabrics and more particularly to filling holders for terry looms for aiding in the production of an even pile throughout the width of the portion of the fabrics which is provided with terry pile.

A terry loom usually employs two sets of warp threads, "ground warps" for making the body of the fabric and "terry warps" for making the loops or pile. In forming the loops or pile, it is the usual practice to partially beat up the filling for a series of picks, known as "loose picks" and designated as first, second, third, etc., depending upon their sequential insertion into the fabric. After the loose picks are inserted, it is the practice to fully beat up the filling upon the succeeding pick, known as a "fast pick," which forces the loose picks against the fell of the fabric causing the terry warps, which are let off at the time of full beat up, to form loops projecting from either or both sides of the fabric.

Some problems have been encountered in the weaving of terry cloth, since the first loose pick which is to be partially beat up is held at the fell of the fabric at one end. To reach the partial beat-up position which is spaced from the fell, the pick angles rearwardly for a substantial distance across the fabric. Once the partial beat-up position is reached, the first loose pick extends the rest of the distance across the fabric substantially parallel to the fell. Subsequent loose picks in the series extend across the fabric in substantial parallelism to the fell of the fabric, since they are not, during partial beat up, bound to the fell at either end thereof and present no problem.

The distance at which the first loose pick is spaced from the fell of the fabric determines the ability of the terry motion to fully take up, for pile loop formation, the amount of terry warp fed for a given height of terry loops. In order to take up the full amount of terry warp fed with each fast pick, it has been determined that the combined friction of three picks of weft (two loose picks and one fast pick) is required to pull the fed terry warp forward to form full pile loops on the fast pick, due to the frictional resistance of the reed, the harnesses, the drop wires and the whip roll on the terry warps. Thus, if the first loose pick extends inwardly from either selvage edge and through the shed, at an angle, for any noticeable distance, the angled portion of the first loose pick does not assist the second loose pick and the fast pick in pulling the terry warp forward through the beating up of the fast pick; that is, the angled portion of the first loose pick will not assist in pulling the pile warp forward until said angled portion is moved forward with the second loose pick. This results in short terry loops being formed on the fast pick across that portion of the fabric defined by the previously angled portion of the first loose pick, with secondary loops being formed on the respective first and second loose picks to take up the slack remaining in the terry warp. The angled portion of the first loose pick, in each instance, usually extends inwardly from the respective selvage edge of the fabric for a distance of from 1½ inches to 3 inches. Thus, the resultant fabric has a narrow warpwise band of pile of uneven height, from 1½ to 3 inches wide, along each side portion of the fabric, which is highly undesirable.

In the past, one means which was developed for achieving parallelization of the first loose pick of a terry series

2

with the fell of the fabric comprises a pair of filling holding needles which are moved into the path of the filling by the terry motion cam and are held in the path of the filling until all of the subsequent loose picks are inserted. The filling holding needles are mounted on the temples of the loom and reciprocated therewith as the reed moves to the partial beat-up position. The needles remain descended into the warp rearwardly of the fell of the cloth at the partial beat-up position and keep the filling parallel until the insertion of the fast pick and the start of the full beat up. Before the full beat up takes place, the needle is raised out of the warp and retarded towards the front of the loom by the terry motion cam. Although this mechanism achieves parallelization of the loose picks, it is not entirely effective since it is very complicated and raises many problems in the adjustment of the complicated cams and linkages employed.

Another means which was developed for keeping the filling parallel comprises a needle which is actuated in response to the movement of the lay to either the full or partial beat-up position. The needle is moved into the path of the filling as the lay is moved rearwardly, and out of the path of the filling each time that the lay is moved forwardly. Difficulties have been encountered in the use of this device, since the first loose pick in a terry series has a tendency to spring into the angled condition after the filling holding needle has been moved out of the path thereof which would cause the filling holding needle to move downwardly on the side of the first loose pick farthest from the fell of the cloth. The same condition which had been encountered before the use of any filling holding means would result since the first loose pick would be in the angled condition at the time of full beat up.

It is the primary object of the present invention to provide an improved apparatus and method for holding the loose picks of a terry series in substantial parallelism with the fell of the fabric until the full beat up thereof by the fast pick.

Another object of this invention is to provide a filling holding apparatus and method in which the filling holder may be withdrawn from the warp with each beat up of the lay and will, nevertheless, always engage and parallelize respective loose pick weft during those portions of the lay movement in which the reed is spaced from the loose picks whereby the apparatus may be actuated by the action of the lay without resorting to complicated and expensive cams and linkages.

A more specific object of the present invention is to provide a simplified apparatus having a sharp-tipped or narrow-ended blade provided with a rearwardly protruding cam surface and means responsive to each rearward movement of the lay, from either the full or partial beat-up position, for moving the blade from a raised to a lowered position closely adjacent the fell of the cloth and into the path of the loose picks as they are inserted into the fabric. The cam surface engages the first loose pick upon its insertion and again, upon the insertion of any subsequent loose pick or loose picks, so that although the first loose pick may return to an angular position upon withdrawal of the blade, the cam surface engages and moves the first loose pick back into substantial parallelism with the fell of the fabric so the changing warp shed may grip said first loose pick and insure its proper parallelism upon occurrence of the subsequent fast pick and slackening of the terry warps. This produces terry loops which are of uniform or predetermined height throughout the width of the fabric.

Some of the objects of the invention having been stated, other objects will appear as the description proceeds when taken in connection with the accompanying drawings, in which—

FIGURE 1 is a fragmentary side elevation of the im-

proved filling holding apparatus in association with a loom temple, lay and warps, with parts broken away and some parts removed for clarity;

FIGURE 2 is a fragmentary plan view of the structure shown in FIGURE 1, with portions broken away, showing the filling holder blade in the path of the respective first loose pick and omitting the lay;

FIGURE 3 is a fragmentary perspective view with some portions broken away, showing the filling holder blade in the raised position out of the path of the loose pick; and

FIGURE 4 is a fragmentary perspective view, with portions broken away, showing the filling holder blade in lowered position, wherein the first loose pick has been slid back between the warps into parallel position relation with the succeeding loose pick.

Referring now to the drawings, the embodiment of the present invention is shown in association with a portion of a terry loom for weaving terry fabric F formed of ground and terry warps W and wefts. Terry loops T are formed on either or both faces of the fabric F. The weft yarn parallelizing or guiding apparatus, broadly designated at 10, includes a support in the form of a plate 11 suitably secured to the outer surface of the left-hand temple 12 adjacent the end thereof nearest to the fell of the fabric. Plate 11 has a pair of fixed pivot shafts 13, 14 projecting outwardly therefrom. A gear quadrant 15 is oscillatably mounted on shaft 13 and has a plurality of teeth 16 thereon. A gear quadrant 20 is oscillatably mounted on shaft 14 and has a plurality of teeth 21 thereon in operative engagement with the teeth 16 on gear quadrant 15.

Gear quadrant 20 has a downwardly projecting portion 22 and an upwardly projecting portion 23. A suitable torsion spring 24 is concentrically mounted on shaft 14 and one end thereof is attached to a collar 14a fixed on shaft 14. The other end of torsion spring 24 is attached to the downwardly projecting portion 22 of gear quadrant 20 by any suitable means such as a screw 25. Torsion spring 24 normally biases gear quadrant 20 in a clockwise direction, as shown in FIGURES 1 and 4, so the upwardly projecting portion 23 engages a stop member or abutment 26 adjustably mounted on plate 11.

Gear quadrant 15 has an outwardly projecting arm 30 formed integral therewith. Arm 30 has a filling holder 31 adjustably attached thereto, by any suitable means such as a screw 33, for clamping the stem of filling holder 31 in a slot 32 formed in the free end of arm 30. Filling holder 31 extends substantially weftwise, at right angles to arm 30 and inwardly toward the fabric, and has a downwardly extending blade 34 formed integral therewith or attached thereto. Blade 34 of the filling holder 31 has a straight front edge 35 and a curved rear edge 36 which come together substantially in a point or relatively narrow free end 37 for reasons to be presently described.

A lay 40 having a reed 41 mounted thereon, by a suitable reed cap 42, is positioned rearwardly of the apparatus 10 and is mounted on the loom and may be oscillated and varied in length of strokes by a suitable variable beat-up mechanism of well-known conventional or other construction. The lay and/or reed move to a plurality of positions. The first of these positions is the back position, rearwardly of that shown in FIGURE 1, which is the position at which the weft is inserted between the warps to form the fabric. The second of these positions is the full or normal beat-up position shown in broken lines in FIGURE 1 wherein the reed 41 has moved the inserted filling to the fell of the fabric. Another of these positions is the partial beat-up position wherein the reed 41 has moved the loose picks to a position wherein the first loose pick is spaced from the fell of the fabric a distance approximately equal to twice the desired height of the loops or pile.

Lay 40 has a bunter 43 mounted on the front face

thereof which is adapted to engage the downwardly projecting portion 22 of gear quadrant 20 to rotate gear quadrant 20 in a counterclockwise direction against the action of torsion spring 24 substantially as shown in broken lines in FIGURE 1, upon the movement of lay 40 to either the partial or full beat-up position. The foremost broken line position of FIGURE 1 is that to which arm 30 and blade 34 move with a full beat-up stroke of lay 40. The other broken line position in which arm 30 and blade 34 are shown corresponds to a partial or loose pick beat-up stroke of lay 40.

In operation, as the lay 40 moves in a backward stroke after the full beat up of a fast pick, the bunter 43 moves out of contact with the downwardly projecting portion 22 of gear quadrant 20. Torsion spring 24 rotates gear quadrant 20 in a clockwise direction, as seen in FIGURE 1, until the upwardly projecting portion 23 engages the stop member 26.

Gear quadrant 20 thus rotates gear quadrant 15 in a counterclockwise direction as seen in FIGURE 1 through the teeth 16, 21. As gear quadrant 15 rotates, the arm 30 moves the filling holder 31 carried thereby downwardly so that blade 34 enters into the path of the subsequently cast weft or filling. The first loose pick in the respective terry cycle is inserted with the weft A extending from the adjacent selavage edge at the fell of the fabric, around the rear edge 36 of the filling holder blade 34, remote from the fell of the fabric F as seen in FIGURE 2. Lay 40 is then moved to the partial beat-up position wherein the reed 41 moves the first loose pick A to the position spaced from the fell of fabric F a distance substantially equal to twice the desired height of the loops or pile.

As lay 40 is moved to the partial beat-up position, bunter 43 engages projecting portion 22 of gear quadrant 20, rotating the gear quadrant in a counterclockwise direction. Gear quadrant 20 rotates gear quadrant 15 in a clockwise direction, thus raising the filling holder 31 out of the path of the filling. Because of the tension in the first loose pick which is caused by the pick being stretched around the filling holder 31, the first loose pick will then assume an angled condition with respect to the fell of the fabric substantially as shown in FIGURE 3.

As lay 40 is again moved to the back position for the insertion of the next succeeding loose pick, filling holder 31 will be moved downwardly in the manner aforementioned. The filling holder is so positioned that the point 37 of blade 34 moves against or in close proximity to the fell of the fabric so that point 37 of the blade 34 will enter between the warps at a point closely adjacent the selavage edge of the fabric and between the fell and the first loose pick which has assumed the aforementioned angled condition. The cam surface 36 of the blade 34 will thus engage the first loose pick and, as the filling holder 31 continues its downward movement, the cam surface 36 will cam the first loose pick rearwardly away from the fell of the fabric in substantial parallelism thereto as shown in FIGURE 4. This action of the filling holder 31 on the first loose pick will occur after the insertion of each succeeding loose pick, such as pick B, until the same is fully beaten up against the fell of the fabric, thus insuring that the first loose pick is in substantial parallelism with the fell of the fabric at the time of full beat up. However, since the warp shed normally changes or is reversed following each beat up of lay 40, the first loose pick A need only be cammed or slid back following insertion of the next succeeding or second loose pick B, the latter pick then being held in substantially the desired position by the crossed warps.

Even then, the blade 34 is further insurance against angular disposition of the first loose pick A.

It is apparent that, since the first loose pick A is maintained in substantial parallelism to the fell of the fabric, the loops or pile T will be of substantially equal height across the full width of the portion of the fabric having

terry pile thereon. It is to be noted that the novel apparatus of the instant invention is of extremely simple and compact construction which requires substantially no maintenance or adjustment. Further, since the filling holder blade 34 is moved out of the path of the filling upon each forward movement of the lay, neither the filling holder nor the reed is damaged by the movement of the reed to the partial or full beat-up positions.

It should be noted that the various movable parts in FIGURES 3 and 4 are shown in respective positions occupied thereby during, and at the end of, a backward stroke of the reed 41 of FIGURE 1. In other words, a second loose pick has been inserted in the warp shed and beat up in FIGURE 3. Thus, the reed 41 is in the course of a backward stroke, the shed has started to reverse or change, and blade 34 has started to move downwardly in a counterclockwise direction as indicated by the arrow on quadrant arm 30. In FIGURE 4, the backward stroke of reed 41 and the shed change have been substantially completed, and the inclined cam surface 36 of filling holder blade 34 has entered the shed and cammed the angled portion of the first loose pick A of FIGURE 3 into parallel relation with the fell of fabric F and with the second loose pick B.

It should be noted that, while only one mechanism has been shown and described, a similar mechanism may be provided on the opposite side of the loom consisting of substantially the same structure, except that it is assembled in opposite-hand relationship. Said similar mechanism is required on any looms which weave an odd number of picks in each terry cycle, because the first loose picks of successive terry cycles are cast from opposite sides of the loom in alternation.

Although the blade 34 is spaced a short distance inwardly of the selvage edge of the fabric F, it should be noted that the remaining, relatively short, angled portion of loose pick A embraces only a narrow, plain-woven, selvage band S which, being devoid of terry loops, presents no problem.

The rear edge or cam surface 36 of blade 34 is shown as a curve, which is desirable. It is contemplated that the lower portion of cam surface 36 may be straight provided that it extends at a relatively broad, but acute, angle relative to the front edge 35 of blade 34 or, at least, relative to the vertical plane of the fell of the fabric F.

In the drawings and specification there has been set forth a preferred embodiment of the invention and, although specific terms are employed, they are used in a generic and descriptive sense only and not for purposes of limitation, the scope of the invention being defined in the claims.

I claim:

1. In a loom for weaving terry fabrics from warps and having loose picks and a fast pick inserted therein in repeated cycles, an oscillatable lay, a reed on said lay, means for moving the reed to a full beat-up position wherein fast and loose picks are moved to the fell of the fabric and to a partial beat-up position wherein loose picks are moved to a point spaced from the fell of the fabric and the first of such loose picks extends inwardly at an angle from the juncture of the fell and at least one selvage of the fabric, filling holding means mounted for movement adjacent to and inwardly of said selvage into and out of the path of the first of the loose picks of each cycle for maintaining the first loose picks in substantial parallelism to the fell of the fabric, means responsive to each beat-up movement of the lay for moving the filling holding means out of the path of the first loose pick, and means biasing said filling holding means into the warps during each backward stroke of the lay and, thus, into the path of the first loose pick of each cycle, said filling holding means being so arranged as to engage the first loose pick between it and the fell upon movement thereof into the path of the first loose

pick after the insertion of the first loose pick and upon the insertion of subsequent loose picks of the same cycle and to move the first loose pick rearwardly in each instance into substantial parallelism with the fell of the fabric.

5 2. In a loom for weaving terry fabrics having loose picks and a fast pick inserted therein in repeated cycles, an oscillatable reed, and means for moving the reed to a full beat-up position wherein the fast and loose picks are moved to the fell of the fabric and to a partial beat-up position wherein the loose picks are moved to a point spaced from the fell of the fabric and the first of such loose picks extends inwardly at an angle from the juncture of the fell and at least one selvage of the fabric; the combination of filling holding means mounted for movement adjacent to and inwardly of said selvage into the path of the first of said loose picks of each cycle for maintaining the first loose pick in substantial parallelism with the fell of the fabric, means responsive to each 10 movement of the reed from each beat-up position to the next succeeding beat-up position for moving said filling holding means into and then out of the path of the first of said loose picks of each cycle, said filling holding means having a cam portion thereon adapted to engage 15 the first loose pick between it and the fell during movement of the filling holding means into the path of the first loose pick upon subsequent insertion of at least one other loose pick of the same cycle to cam the first loose pick rearwardly into substantial parallelism with the fell 20 of the fabric.

25 3. In a loom for weaving terry fabrics having warps and loose picks and a fast pick inserted in said warps in repeated cycles, an oscillatable reed, and means for moving the reed relative to the fell of the fabric to full beat-up position wherein the fast and loose picks are moved to the fell of the fabric and to partial beat-up position wherein the loose picks are moved to a point spaced from the fell of the fabric and the first of such loose picks extends inwardly at an angle from the juncture of the fell 30 and at least one selvage of the fabric; the combination of a filling holder mounted on said loom adjacent to and inwardly of said selvage for movement between a first position between the fell of the fabric and the partial beat-up position of the reed in the path of the loose picks and a second position out of the path of the picks and removed from between the fell of the fabric and the partial beat-up position of the reed, means biasing said filling holder toward the first position, and means responsive to each beat-up movement of the reed for moving the filling holder from the first to the second position, said filling holder having a cam surface thereon which enters the path of the loose picks between the same and the fell of the fabric and is adapted to engage the first of the loose picks in each instance and cam the same rearwardly 35 into substantial parallelism with the fell of the fabric.

4. In a loom for weaving terry fabrics having at least two loose picks and a fast pick inserted in alternation, an oscillatable lay mounted for movement on said loom, a reed mounted on said lay for movement therewith, said 40 loom being of a type effecting relative movement between the fell of the fabric and the beat-up point of said reed such as to cause the reed to occupy a full beat-up position wherein the fast and loose picks are moved to the fell of the fabric and to occupy a partial beat-up position spaced from the full beat-up position wherein the loose picks are moved to a point spaced from the fell of the fabric, said reed being caused to occupy the full beat-up position only after the insertion of a fast pick and to occupy the partial beat-up position after the insertion of 45 a loose pick; the combination therewith of a filling holder mounted on said loom adjacent to and inwardly of said selvage for movement between a first position between the fell of the fabric and the partial beat-up position of the reed in the path of the loose picks and a second position out of the path of the picks, means responsive 50 to each beat-up movement of the lay for moving the filling holder from the first to the second position, and means responsive to each beat-up movement of the reed for moving the filling holder from the second to the first position, said filling holder having a cam surface thereon which enters the path of the loose picks between the same and the fell of the fabric and is adapted to engage the first of the loose picks in each instance and cam the same rearwardly 55 into substantial parallelism with the fell of the fabric.

5. In a loom for weaving terry fabrics having at least two loose picks and a fast pick inserted in alternation, an oscillatable lay mounted for movement on said loom, a reed mounted on said lay for movement therewith, said 60 loom being of a type effecting relative movement between the fell of the fabric and the beat-up point of said reed such as to cause the reed to occupy a full beat-up position wherein the fast and loose picks are moved to the fell of the fabric and to occupy a partial beat-up position spaced from the full beat-up position wherein the loose picks are moved to a point spaced from the fell of the fabric, said reed being caused to occupy the full beat-up position only after the insertion of a fast pick and to occupy the partial beat-up position after the insertion of 65 a loose pick; the combination therewith of a filling holder mounted on said loom adjacent to and inwardly of said selvage for movement between a first position between the fell of the fabric and the partial beat-up position of the reed in the path of the loose picks and a second position out of the path of the picks, means responsive 70 to each beat-up movement of the lay for moving the filling holder from the first to the second position, and means responsive to each beat-up movement of the reed for moving the filling holder from the second to the first position, said filling holder having a cam surface thereon which enters the path of the loose picks between the same and the fell of the fabric and is adapted to engage the first of the loose picks in each instance and cam the same rearwardly 75 into substantial parallelism with the fell of the fabric.

to the effecting of each full beat-up position and each partial beat-up position of the reed for moving the filling holder from the first to the second position, and means biasing said filling holder toward the first position, said filling holder having a cam portion thereon provided with a narrow free end merging with an inclined cam surface which enters the path of the loose picks between the same and the fell of the fabric and which is adapted to engage the first of the loose picks in each instance and cam the same rearwardly into substantial parallelism with the fell of the fabric.

5. In a loom for weaving terry fabrics from warps of which a shed is formed and from loose and fast picks of weft, said loom having a beating means movable in active and inactive strokes, and means for varying the relative positions of the beat-up point of the beating means and the fell of the fabric being woven so as to produce loose and fast picks in repeated cycles in which the loose picks are beat up in spaced relation to the fell of the fabric and said fast picks are beat up against the fell and carry the loose picks therewith in each cycle, and wherein the first loose pick of each cycle is inserted so that it extends from one selvage edge of the fabric at a point in alinement with the fell and inwardly through the shed at an angle to the fell; the combination therewith of a filling holder having a relatively sharp free end and being movable into the shed perpendicular to the picks of weft and adjacent said selvage, said filling holder having a cam surface which, when positioned within the shed, extends at an angle upwardly and away from the fell of the fabric so that its portion then alined with the picks of weft is spaced from the fell a distance substantially equal to the distance from the fell at which loose picks are beat up by said beating means, means for withdrawing said filling holder from the shed with each active stroke of said beating means, means for inserting said filling holder through the shed with each inactive stroke of said beating means, and said filling holder being movable by said last-named means in such a path that its relatively sharp end moves in close proximity to the fell of the fabric to insure that the same enters the shed between the fell and the first loose pick of each cycle whereby said cam surface moves the angled portion of the first loose pick away from the fell and into substantially parallel relation to, but spaced from, the fell during the insertion of any succeeding loose picks and the fast pick of each respective cycle.

6. A method of weaving on a terry loom and parallelizing loose picks of weft which are beat up in a shed of warps in spaced relation to the fell of terry fabric during a loop forming cycle and wherein said loose picks are beat up against the fell by a fast pick in each cycle; said method comprising inserting a first loose pick through the shed and past a filling holder projecting through the

- shed at a point closely adjacent the respective selvage edge and the fell of the fabric, beating up said first loose pick in spaced relation to the fell while withdrawing the filling holder from the shed whereby said first loose pick extends at an angle from the selvage edge and from the fell through the shed, then changing the shed, then again inserting said filling holder through the shed at said point between the angled first loose pick and the fell while utilizing the filling holder to cam said first loose pick away from the fell so that it extends in parallel relation to the fell, inserting and beating up at least one second loose pick in spaced relation to the fell while again withdrawing the filling holder from the shed, then inserting a fast pick through the shed while again moving said filling holder into the shed at said point and between the first loose pick and the fell, and then beating up said fast pick with the first and second loose picks against the fell, while again withdrawing the filling holder from the shed, in the forming of terry loops.
- 20 7. A method of weaving on a terry loom utilizing a filling holder blade having an inclined rear surface for parallelizing loose picks of weft beat up in a shed of warps in spaced relation to the fell of terry fabric during a terry loop forming cycle and wherein said loose picks are beat up against the fell by a fast pick in each cycle; said method comprising inserting a first loose pick through the shed and past the inclined surface of the filling holder blade projecting through the shed at a point closely adjacent the respective selvage edge and the fell of the fabric, beating up said first loose pick in spaced relation to the fell while withdrawing the blade from the shed whereby said first loose pick extends from the fell and the selvage edge inwardly through the shed at an angle to the fell, then changing the shed, again inserting said blade through the shed at said point between the angled first loose pick and the fell while causing the inclined surface to cam said first loose pick away from the fell so that it extends in parallel relation to said fell, inserting and beating up at least one second loose pick in spaced relation to the fell while again withdrawing the blade from the shed, then inserting a fast pick through the shed while again moving said blade into the shed at said point and between the first loose pick and the fell, and then beating up said fast pick with the first and second loose picks against the fell while again withdrawing the blade from the shed in the forming of terry loops.
